UNITED STATES PATENT OFFICE.

WILLIAM G. R. BRAEMER, OF CRANSTON, RHODE ISLAND, ASSIGNOR TO AMERICAN MOISTENING COMPANY, A CORPORATION OF MAINE.

HUMIDIFIER.

Application filed November 11, 1922. Serial No. 600,236.

To all whom it may concern:

Be it known that I, WILLIAM G. R. BRAEMER, a citizen of the United States, and resident of Cranston, county of Providence, 5 and State of Rhode Island, have invented an Improvement in Humidifiers, of which the following is a specification.

The object of my invention is to provide an efficient construction of humidifier, for 10 use more particularly in textile and other mills and places where a substantially constant humidification of the air is desired, the same comprising an individual unit adapted to be supported from a wall or post in the 15 room and having an electrically driven disk structure of special construction for causing an outward flow of water and air at its perimeter, combined with improved features for sub-dividing the said water into a mist 20 by mechanical impact therewith and for subjecting the mist to currents of air in such manner as to cause it to pass outward into the room, my improvement residing 25 more particularly in means for handling the water, dissipating it into a mist, and controlling the air currents for transferring the mist from the machine into the surrounding atmosphere.

With the above and other objects in view, 30 the nature of which will be more fully understood from the description hereinafter, the invention consists in the novel construction of humidifier, as hereinafter more fully described and defined in the claims.

Referring to the drawing: Fig. 1 is a side elevation with portions in section illustrating the general nature and construction of my improved humidifier and its supporting means; Fig. 2 is a front view of the same; 40 Fig. 3 is a perspective view of a portion of the helically coiled metal ribbon constituting the dissipating means; Fig. 4 is a similar view of a modification of the same; and Fig. 5 is a transverse section of a portion 45 of Fig. 1, taken on line 5—5 thereon.

2 is an electric motor of any suitable construction and, as shown, is supported upon a bracket 3 through a pedestal 4, formed as an extension of the bracket and to the top 50 of which the motor is bolted. The electric motor is provided with a shaft 5 carrying at its forward end a revolving disk 6 and at its other end a propeller or fan 7 for forcing currents of air about the motor and 55 in a direction toward the disk 6. More par-

ticularly, the disk 6 comprises a circular front plate 8 secured at its central part to a hub 9 which is screwed upon the ends of the motor shaft 5 and locked thereon by a lock nut 10, and provided with a more or less 60 conical sheet metal portion 11 secured to the disk and to a flange of the hub 9 in such manner as to provide a forward and outwardly curved inner wall extending to and blending into the plate 8 of the disk 65 structure. An annular plate 12, having the same external diameter as the plate 8, is arranged immediately to its rear and the two plates are spaced apart and riveted or otherwise secured together at 13, leaving between them a narrow annular passage 14 which is unobstructed in a vertical plane excepting for the presence of the rivets. The inner end of the annular plate 12 is curved 70 rearward, as at 15, and providing an opening directed toward the motor adapted to receive air from the fan. The two curved portions 11 and 15 of the disk structure provide between them an annular air passage 16 whose forward curvature blends into the 75 radial passage 14 between the plates 8 and 12, said air passage 16 gradually decreases in cross sectional area so that the air currents which enter the said passage will be, under the rapid rotation of the disk, caused 80 to travel with increasing velocity radially outward through said passage and the annular passage 14, and in so doing assist in an outward propulsion of the water which is delivered to the curved portion 11 by the 85 nozzle 17 and which under centrifugal action flows radially along the inner surface of the plate 8 and through the passage 14. The water which is delivered from the nozzle 17 to the revolving disk near its center 90 may be supplied in any suitable manner from a pipe 18 under the control of a valve 19, the latter being either manually operated or automatically controlled hygrostatically in any of the usual manners well 95 known in the art of humidification. 20 is a disk secured to and revolving with the motor shaft 5 to prevent any possibility of water entering the bearing of the motor. As is shown, the rear end of the part 15 ex- 100 tends beyond the rear end of the hub portions 9 and 11 of the disk plate 8, so that in case any water from the nozzle 17 flows 105 backward off the hub portion of the disk, it will pass downward between the parts 11 110

and 15 and, by gravity, or centrifugal force, as the case may be, be delivered through the passage 14 of the disk structure.

Immediately surrounding the revolving disk structure 6 is arranged a helical coil of metal 21 in circular form, the inner portion thereof being slightly separated from the perimeter of the revolving disk structure 6. In the preferred construction, the 5 helical coil of metal is preferably formed from a sheet metal ribbon, as 22, coiled on edge (Fig. 3), so as to present a series of parallel flattened surfaces arranged in a circle and with their inner edges toward the 10 perimeter of the disk. This helical structure 21 is soldered or otherwise secured to the outer edge of a conical shell 23 extending rearwardly and inwardly like a truncated cone, the same being open at its rear end. 15 Secured to the outer wall of the shell 23 is an annular cone-shaped shell 24 whose perimeter 25 is curved and extends over the outer portion of the coil and is preferably secured thereto as a support for it, said coil 20 being shielded between the perimeters of the shells 23 and 24 with the exception of approximately one-third of its circumference on that portion of it which is directed toward the revolving disk and to the forward part of the machine, as will be clearly 25 understood by reference to Fig. 1. In this manner, the film of water extending out from the perimeter of the disk is rapidly brought into contact with the edges of the 30 ribbon coil and caused to be broken up and dissipated into a mist. The air currents from the propeller or fan in their forward passage are partly guided into the annular space 26 between the cone shaped shell 23 35 and the plate 15 of the disk and said currents are directed across the space between the helical structure 21 and the perimeter of the revolving disk, so as to force the vapor formed by the co-action of these parts 40 outwardly into the room. Furthermore, the air which flows through the annular passage 26 and through the annular passage 17 in the disk conjointly cause the air to flow between the helical plates of the structure 45 21 as well as in a horizontal direction below the same, thereby tending to keep the said helical portions of the structure 21 (which directly cooperate with the revolving disk) clear of water. Any water which 50 is not dissipated is permitted to find egress from the coil 21 backward into the space 27 formed between the parts 23 and 24 and thence, by gravity, pass to the bottom and into the trough 28 from which it may 55 escape by drain pipe 29.

Arranged about the shells 23 and 24 and their associated parts is an outer shell or casing 30 which is also of general conical shape, but having its largest diameter 60 curved, as at 31, to provide a grooved chan-

nel in a vertical plane as at 32 leading down each side to the bottom trough shaped portion 28 from which the drain 29 extends, so that any surplus water which may be projected radially from the disk may find its way beyond the helical structure and be collected by the grooved construction of the casing and delivered to the drain. The shell 30 provides between itself and the shell portions 23 and 24 an annular passage 33 through which air from the propeller or fan passes and which is directed forward and slightly inward at the front portion of the machine, so that it assists in propelling the vapor into the room and at the same time thoroughly comingling with said vapor to lower its relative humidity to approximately that which would be required with a given supply of water. 34 is a casing arranged about the motor and the propeller or fan and is open at the rear for receiving the air and is connected at its forward end into the rear or smaller end of the casing shell 30, said casing 34 insuring that all of the air put in motion by the propeller or fan shall reach the passages 33, 26 and 16, to the fullest extent. For stability, the pedestal 4 which supports the motor is provided with a forward arm or bracket 35 to which the casing shell 30 is bolted; and it also supports the inner shells 23 and 24 inasmuch as they are themselves supported by the casing shell 30 by means of the spacing rivets 36.

While I prefer that the helical metal structure shall be made of a flat metallic ribbon coiled on its edge, as shown in Fig. 3, I do not confine myself to that exact cross section of the metal.

In Fig. 4, I have shown the coil as formed of wire of square cross section and it will be understood that it might be of any other shape, so long as it provides the plurality of obstructing surfaces with which the water film is required to come in contact.

In the use of the apparatus forming my invention, it will be manifest that the air currents are utilized to the fullest advantage, more particularly by dividing them up and utilizing the different portions so formed, each for its specific purpose and finally in conjoint action. For instance, the air currents passing through the passage 16 of the disk assist, through their own force and the centrifugal action given to them by the disk, to produce an increased velocity to the water film and also tending to make the film more readily converted into mist when it impinges upon the helical structure 21. The air currents passing through the annular passage 26 converge in a concentrated action between the perimeter of the disk and the inner edges of the helical structure and in a transverse direction to the currents from the passage 16 to blow or

carry the aqueous mist outward into the room and away from the helical structure, the air currents passing through the annular passage 33 assist further in forcing the 5 aqueous vapor out into the room and supplying an additional atmosphere of air to reduce the relative humidity. It will also be observed that the helical coiled structure is shielded upon its outer portion 10 against the action of the air passing through the annular passage 33 so that no spray particles of water will be driven outwardly into the atmosphere by said air currents. It will also be seen that the shell 23 so connects 15 with the bottom of the helical coil 21 that the air currents passing through the passage 26 are directed only toward the operative portion of the coil and hence upon that portion of the mist which is brought to the finest 20 sub-division. It will also be seen that neither the currents of air in the passages 26 or 33 in any manner act upon those portions of the helical coil 21 wherein the water in dense or spray condition might find its 25 way and consequently said non-vaporized portions of the air are free to escape through the shielded channel 27 for being conveyed out of the air currents. The result of this 30 is that the humidified air which passes into the room is devoid of objectionable spray and approximates the humidified condition which is produced in the more elaborate humidifiers in which aqueous vapors under temperature conditions are employed in insuring 35 the proper humidification.

It will now be apparent that I have devised a novel and useful construction which embodies the features of advantage enumerated as desirable, and while I have in the 40 present instance shown and described the preferred embodiment thereof which has been found in practice to give satisfactory and reliable results, it is to be understood that I do not restrict myself to the details, 45 as the same are susceptible of modification in various particulars without departing from the spirit or scope of the invention.

Having now described my invention, what I claim as new and desire to secure by Letters Patent is:—

1. A humidifier, comprising a revolving disk having a shallow radial passage providing a peripheral opening and also having an opening to the rear of the disk about its axis, a motor for revolving the disk, an annular row of obstructions arranged about the disk and at a slight distance from its periphery, means for delivering water to the disk whereby it may flow through the 55 radial passage, a fan to deliver a current of air into the radial passage of the disk whereby it is directed as a circular film of small thickness toward its periphery and the row of obstructions for increasing the flow of 60 the water, and a stationary shell between 65

the fan and the annular row of obstructions for directing a separate portion of the air currents entirely separate from the water through the shell and transversely across the annular space between the periphery of 70 the disk and the annular row of obstructions.

2. The invention according to claim 1, wherein further the annular row of obstructions is formed by a helical coil of 75 sheet metal held stationary and out of contact with the revolving disk and water supply pipe.

3. The invention according to claim 1, wherein the annular shell is extended as a 80 shield at the rear of the annular row of obstructions and extending circumferentially over the same, whereby they are exposed only at their outer portions.

4. A humidifier, comprising a revolving 85 disk having a shallow radial passage providing a peripheral opening and also having an opening to the rear of the disk about its axis, a motor for revolving the disk, an annular row of obstructions arranged about 90 the disk at a slight distance from its periphery and formed of a helical coil of sheet metal, means for delivering water to the disk whereby it may flow through the radial passage, a fan to deliver a current of 95 air into the radial passage of the disk and toward its periphery and the row of obstructions, a stationary annular shell between the fan and the annular row of obstructions for directing a separate portion of the air currents through the shell and transversely 100 across the annular space between the periphery of the disk and annular row of obstructions, said shell extended as a shield 105 at the rear of the annular row of obstructions and circumferentially over the same whereby they are exposed only at their outer portions, and wherein further, said annular shell provides an annular passage 110 back of the row of helically formed obstructions for permitting escape of the water which may pass to the rear of said obstructions and delivering it as waste unaffected by the air currents.

5. A humidifier, comprising a revolving 115 disk having a shallow radial passage providing a peripheral opening and also having an opening to the rear of the disk about its axis, a motor for revolving the disk, an annular row of obstructions arranged about 120 the disk at a slight distance from its periphery, means for delivering water to the disk whereby it may flow through the radial passage, a fan to deliver a current of air into the radial passage of the disk and toward 125 its periphery and the row of obstructions, a stationary annular shell between the fan and the annular row of obstructions for directing a separate portion of the air currents through the shell and transversely 130

- across the annular space between the periphery of the disk and annular row of obstructions, said shell extended as a shield at the rear of the annular row of obstructions and 5 circumferentially over the same whereby they are exposed only at their outer portions, and wherein further, there is provided an outer enclosing casing forming a passage for air currents from the rear over the annular shell and its shielding extension whereby air currents pass to the front of the humidifier without acting upon the mist in the annular row of obstructions.
- 10 6. The invention according to claim 5, wherein the outer casing at its forward part provides an annular trough-like perimeter in the plane of the disk and having a drain pipe in communication with its lower portion for carrying away collected water.
- 15 7. The invention according to claim 1, wherein the disk structure has its hub portion made with a curved outer surface blending into the rear wall of the front plate of the disk and in which the rear plate of the disk is curved backwardly to provide between it and the hub an annular air passage leading into the peripheral passage of the disk and in which further the pipe for leading the water to the disk opens into this 20 passage.
- 25 8. A humidifier, comprising a revolving disk having a shallow radial passage providing a peripheral opening and also having an opening at the rear of the disk about 30 its axis and enclosing a hub portion made with a curved outer surface blending into the rear wall of the front plate of the disk the rear plate of the disk being curved backward to provide between it and the hub an 35 annular air passage leading into the peripheral passage of the disk, an annular row of obstructions arranged about the disk and at a slight distance from its periphery, a pipe 40 for delivering water into the annular air passage between the hub and the backwardly curved rear disk plate whereby it may flow by centrifugal action into the radial passage, a fan to deliver a current of air into the annular air passage and thence into the radial 45 passage of the disk, and toward its periph-

55 ery and the row of obstructions, and a stationary shell between the fan and the annular row of obstructions for directing a separate portion of the air currents through the shell and transversely across the annular space between the periphery of the disk and the annular row of obstructions, said stationary shell being made conical like a frustum of a cone and forming between it and the rearwardly curved plate of the disk an 60 annular air passage tapering in area from the rear to the annular row of obstructions, whereby the air current is increased in passing to and transversely between the perimeter of the disk and the annular row of obstructions.

65 9. The invention according to claim 8, wherein further there is provided an outer enclosing casing extending about the annular row of obstructions to provide a passage for 70 air outside of the stationary shell and annular row of obstructions and for directing air forwardly, said casing also providing a trough-like structure for collecting unvaporized water, and a drain pipe leading therefrom.

75 10. In a humidifier, an annular row of obstructions arranged in a vertical plane, combined with a disk revolving in a vertical plane within the annular row of obstructions and consisting of a circular solid plate, an annular plate at its rear and secured thereto in close spaced relation to provide a shallow radial passage between them, said annular plate having its central portion extending rearwardly and providing a large opening, the center portion of the front plate having a hub formed with an outer curved surface blending into the rear wall of the plate, a pipe extending into the space between the hub portion and outer curved portion for delivering water currents to the disk between the hub portion and rearwardly extending annular disk portion, and a fan 80 for delivering a blast of air also into the space between the hub portion and rearwardly extending annular disk portion.

85 In testimony of which invention, I hereunto set my hand.

WILLIAM G. R. BRAEMER.
